WEAVING LOOM

Ernst Egli, Ruti, Switzerland, assignor to Maschinenfabrik Ruti vormals Caspar Honegger, Ruti, Zurich, Switzerland

Application December 6, 1935, Serial No. 53,216
In Switzerland January 4, 1935

6 Claims. (Cl. 139—84)

In weaving looms without superstructure, as well as in looms with superstructure, freedom of movement of the healds is an indispensable requirement. The modern tendency in weaving 5 loom construction—especially in connection with silk weaving—is to reject looms with superstructure, since the latter impedes supervision and accessibility; moreover, particles of oil and dust and so forth falling on the warp and other circumstances related to the access of light have 10 an unfavorable effect upon the quality of the goods and the efficiency of the weaving.

On the other hand, weaving looms without superstructure and with downwardly pulled 15 healds have not established themselves in practice owing to constructional defects and undue stiffness of the heald movement occasioned by positively guided operating arms, which have prevented all freedom of movement of the healds.

20 Now, the present invention provides, in a weaving loom having a free space above the reed and the harness, the feature that the guide and pull members adapted to operate the healds in a suspended manner, are disposed laterally at 25 heald level. This arrangement, while retaining the greatest possible freedom of movement of the healds, greatly facilitates the handling of the aforesaid members, e. g. when attaching the harness cones and heald operating levers, inasmuch as these members are located about half 30 as high from the ground as hitherto.

The accompanying drawing shows two typical embodiments of the invention.

Fig. 1 shows an example for two-heald or 35 plain fabric; and

Fig. 2 one for dobby weave fabric, that is fabric woven by means of dobby controlled healds.

In the weaving loom with free space above the loom and the harness shown in Fig. 1, *a* indicates 40 the top beam, *a*¹ the lower beam of the heald frames, *a*² the side walls of the same, *b* two screws disposed laterally on each of the said frames for adjusting the position of the healds and the size of the shed, *c* two pull chains, *d* 45 two guide rollers, journaled upon pivots parallel to the warp and *e* two harness operating cones. *f* denotes the means for controlling the position of the heald frames. It will be seen that the healds have the greatest possible freedom of movement laterally and in warp direction and that the harness operating cones may be attached at heald level, whereby the connection of the harness cones is considerably facilitated. In other words the point of attachment 50 of the cones *e* to the chains *c* is within the range

of movement of the heald frames. The springs *f* do not hinder the swinging movements of the healds.

In the example according to Fig. 2, for dobby weave fabric, *a* again denotes a heald frame, *b* the adjusting screws for the healds, *c* the pull chains, and *d* the guide rollers. *e*¹ denotes a dobby operated shedding lever, and *f* the springs for returning the heald frames to the lowermost position. Here too, the healds have the greatest 10 possible freedom of movement, and the operating levers of the dobby may be attached at heald level for facilitating the handling.

What I claim is—

1. A weaving loom comprising a plurality of 15 heald frames consisting of an upper top beam, a lower beam and connecting side walls, shafts extending laterally to the side walls of the beams and parallel to the warp, guiding pulleys supported by the shafts and being disposed at a 20 level with the top beam, pull members passing over the guiding rollers, being connected to the side walls of the heald frame and supporting the latter in a suspended manner.

2. A weaving loom comprising a plurality of 25 heald frames consisting of an upper top beam, a lower beam and connecting side walls, shafts extending laterally to the side walls of the beams and parallel to the warp, guiding pulleys supported by the shafts and being disposed at a 30 level with the top beam, pull members passing over the guiding rollers, being connected to the side walls of the heald frame and supporting the latter in a suspended manner at a point situated beneath the top beam.

3. A weaving loom comprising a plurality of 35 heald frames, consisting of an upper top beam, a lower beam and connecting side walls, shafts extending laterally to the side walls of the beams and parallel to the warp, guiding pulleys supported by the shafts and being disposed at a 40 level with the top beam, pull members passing over the guiding rollers being connected to the side walls of the heald frame and supporting the latter in a suspended manner, at a point which is situated underneath the top beam about one third of the distance between the two beams.

4. A low built, compact loom comprising a 45 plurality of heald frames consisting of an upper top beam, a lower beam and connecting side walls, shafts extending laterally to the side walls of the beams and parallel to the warp, guiding pulleys supported by the shafts and being disposed at a level with the top beam, pull members and harness frames, the pull members be- 50 55

ing disposed laterally of said harness frames and passing over the guiding rollers, said pull members also being connected to the side walls of the heald frame and supporting the latter in a suspended manner.

5. A low-built and compact loom comprising a plurality of heald frames consisting of an upper top beam, a lower beam and connecting side walls, shafts extending laterally to the side walls of the beams and parallel to the warp, guiding pulleys supported by the shafts and being disposed at a level with the top beam, pull members and harness frames, the pull members being disposed laterally of said harness frames and passing over the guiding rollers, said pull members also being connected to the side walls of the heald frame and supporting the latter in a suspended manner, at a point located below the top beam.

6. A low-built and compact loom comprising a plurality of heald frames, consisting of an upper top beam, a lower beam and connecting side walls, shafts extending laterally to the side walls of the beams and parallel to the warp, guiding pulleys supported by the shafts and being disposed at a level with the top beam, pull members and harness frames, the pull members being disposed laterally of said harness frames and passing over the guiding rollers, said pull members also being connected to the side walls of the heald frame and supporting the latter in a suspended manner at a point which is situated underneath the top beam about one third of the distance between the two beams. 15
